US00D714011S

(12) **United States Design Patent**
Fredendall et al.

(10) **Patent No.:** **US D714,011 S**
(45) **Date of Patent:** **** Sep. 23, 2014**

(54) **SHOPPING CART COMPONENT**

(71) Applicant: **Retail Design Services, LLC**,
Northfield, MN (US)

(72) Inventors: **Jonathon A. Fredendall**, Buffalo, MN
(US); **John Robert Ebling**, Northfield,
MN (US); **Jay Robert Stemler**, Elk
River, MN (US); **Gary Robert Ebling**,
Northfield, MN (US)

(73) Assignee: **Retail Design Services, LLC**,
Northfield, MN (US)

(**) Term: **14 Years**

(21) Appl. No.: **29/451,076**

(22) Filed: **Mar. 27, 2013**

Related U.S. Application Data

(62) Division of application No. 29/436,561, filed on Nov. 7, 2012, now Pat. No. Des. 681,901, which is a division of application No. 29/406,240, filed on Nov. 10, 2011, now Pat. No. Des. 672,932.
